CHARLES SPAETH, OF FLUSHING, NEW YORK, ASSIGNOR TO NE-ARGA CORPORATION, OF NEW YORK, N. Y., A CORPORATION OF NEW YORK

LAMP STARTING DEVICE

Application filed January 18, 1930. Serial No. 421,682.

This invention relates to starting devices for mercury arc lamps and similar apparatus.

It is an object of my invention to provide a starting means for mercury arc lamps or similar electrical discharge devices, which is so arranged as to start operation of the lamp and then remain ineffective until it is intentionally made effective again.

In the production of talking moving pictures it is important to have, as nearly as possible, a complete absence of all unnecessary noises and electrical disturbances. Mercury arc lamps equipped with starting devices of the type known heretofore are 15 unsuitable for use in the production of talking pictures because when one of the lamps becomes extinguished, the starting device thereof immediately starts to function so as to reignite the lamp, thereby producing a clicking noise. The noise produced by the ordinary starting device is sufficient to cause a serious disturbance, which will be made part of the sound record. Likewise, when the starting device serves to create a momentary high potential starting current, the starting current causes a disturbance in the recording of the sound if an electrical process is being used. This recording is usually carried out by electrical recording apparatus, 30 including a high power amplifier which serves to amplify the sound currents picked up through microphones. These amplifiers are sufficiently powerful to pick up the disturbing electrical waves as well, thereby impressing on the recording medium an undesired noise.

In accordance with my invention I provide means responsive to initiation of operation of the lamp to render inactive the starting mechanism thereof so that if the lamp later becomes extinguished, the starting device will be unable to function. The lamp will therefore remain unlit until it is manually restored to operation at an opportune moment. I accomplish this result by providing relay means which serves to open the energizing circuit of the starting device upon the creation of a self-sustained discharge through the tube.

The objects and advantages of my inven-

tion and the manner of attaining them will be made clear in the following description and accompanying drawing.

In the drawing, reference numeral 1 indicates a mercury arc tube or other illuminating device requiring a high starting potential. 2 indicates generally an inductive make-and-break starting device of the well-known type, and 3 indicates generally a relay mechanism for rendering inoperative the starting device 2 responsive to the initiation of normal operation of tube 1. 4 is a main line switch for controlling the energy supplied by power line 5.

When it is desired to put the tube 1 into 65 operation, the main line switch 4 is closed, thereby causing a potential to be applied across the electrode terminals 6 and 7 of the tube. This potential, while sufficient to maintain operation of the tube, is not sufficient to start such operation. Closure of the line switch 4 also causes current to flow through conductor 8, ballast resistance 9, contacts 11 of switch 12, current limiting resistance 13, contacts 14 of switch 15, inductance coil 16 75 and back to the line. This current magnetizes the core of the inductance coil 16, thereby causing it to attract the tiltably mounted armature 17, to which is affixed the switch 15. This tilting action causes the circuit to be 80 broken between the contacts 14. Upon breakage of this circuit a high potential surge is set up by the inductance coil 16, which is applied to the terminals 6 and 7 of the tube 1, thereby causing the gas or mercury therein to 85 be rendered conductive so that a discharge is initiated. Immediately after the discharge is created the operating potential necessary for the tube drops sufficiently to enable the tube to continue operation in the normal manner 90 directly from the power source 5.

As current starts to flow through the tube 1, the core 18 of a solenoid or relay, indicated generally by 19, is caused to be magnetized. This core then attracts pivotally mounted 95 armature 20 upon which the switch 12 is mounted. This action causes the connection between contacts 11 to be broken, thereby rendering the starting mechanism 2 inoperative. Upon the attraction of the armature 20 100

by the core 18, contacts 21 are closed, thereby causing a current to pass through a high resistance holding magnet coil 22 which now is connected directly across the terminals of the

5 power line 5. The current through this holding coil is limited by the high resistance of the winding thereof and by the ballast resistance 9. Should the discharge of the tube 1 now be extinguished, as by a cooling blast of

10 air or a momentary change of line potential, the starting device 2 will be unable to operate, because its energizing circuit is broken at 11. In order again to put the tube in operation, it is necessary momentarily to open the line

15 switch 4, thereby deenergizing the holding coil 22 and permitting the contacts 11 of the switch 12 to close. The closure of these contacts permits the starting operation to be repeated in the manner above described. Upon

20 tilting of the armature once or several times, a sufficiently high potential is supplied to the tube to cause the discharge again to be created.

While I have shown a separate holding coil 22, it will be understood that a portion or all 25 of the main coil 23 of the relay 19 might be used instead to maintain the contacts 21 closed.

The function of condensers 23 and 24 to prevent arcing at contacts 14 and 11. The 30 condenser 23 also serves to increase the potential generated by the inductance 16.

As a result of the means and circuit connections which I have just described undesired operation of the starting mechanism of a 35 gaseous discharge device may be prevented, once the line switch is closed and the tube initially put into operation. Further functioning of the starting mechanism is prevented until such time as it is desired, when 40 it may be rendered operative again by opening the line switch momentarily and again closing it. It is therefore possible by such arrangement to prevent undesired audible and electrical disturbances which might interfere with the recording of sound effects.

45 What is claimed is:

1. In a current supply system, an electric lamp, a source of power and a control switch therefor, a starting device having a circuit in 50 shunt to said lamp, a switch therefor, and means responsive to the starting of operation by said lamp, for opening and holding open said switch second mentioned, said means comprising an armature, an associated magnetizing coil connected between said lamp and said circuit, said magnetizing coil having a winding in series with said lamp, and a separate holding winding, and contact means responsive to the opening of said switch second 55 mentioned for energizing said holding winding.

2. In a current supply system, a lamp requiring means for reducing the starting resistance of the current path thereof, a power 60 source and a control switch for said lamp, a

starting device for performing the function above mentioned, and means responsive to the desired reduction in starting resistance for rendering said starting means ineffective until said control switch is open.

70 In testimony whereof, I have signed my name to this specification, this 16th day of January, 1930.

CHARLES SPAETH.
